BAG FOR GOLF CLUBS

Milton Rashkow, Manhattan, N.Y., assignor to Michael Davis, Inc., Brooklyn, N.Y., a corporation of New York

Filed Mar. 17, 1965, Ser. No. 84,324

Term of patent 14 years

(Cl. D34—5)

FIG. 1

FIG. 2

FIG. 3

FIG. 4

FIG. 5

FIG. 6

FIG. 1 is a perspective view of a bag for golf clubs showing my new design;

FIG. 2 is a rear elevational view thereof;

FIG. 3 is a top plan view thereof;

FIG. 4 is a front elevational view thereof;

FIG. 5 is a side elevational view thereof showing the side opposite from the side shown in FIG. 1; and

FIG. 6 is a bottom plan view thereof.

I claim:

The ornamental design for a bag for golf clubs, substantially as shown.
